UNITED STATES PATENT OFFICE.

FRANK S. CHRISMAN, OF SOUTH BEND, INDIANA.

METAL BINDING FOR REED MATTING.

Application filed January 25, 1926. Serial No. 83,747.

The invention relates to metallic bindings for reed matting, particularly of the type used in making bodies of baby cabs and doll baby cabs or carriages, and has for its object 5 to provide a metallic binding, which may be easily and quickly applied to the upper marginal edge of the reed walls of the body of the carriage, and which may be easily and quickly bent to form over the marginal edges 10 of the walls, and has sufficient rigidity to maintain its form and the form of the body, thereby obviating the expensive operation of providing a wooden binding which has to be bent to form after a steaming operation and 15 which also involves the slow and laborious operation of applying the binding to the walls by a tacking or other securing operation. The metallic binding obviates splitting which is a common difficulty experienced in 20 wooden bindings and will wear indefinitely.

A further object is to first apply the metallic binding to the marginal edge of the sheet of matting in the form of a channel with one flange engaging one side of the 25 strands or reeds and the other flange engaging the other side of the strands or reeds and then bending the channel onto itself, thereby folding the strand onto themselves in substantially parallel relation for securely locking 30 and holding the binding on the edge of the sheet of matting, and after which the sheet of metal and binding can be readily bent to form.

A further object is to provide a metallic 35 binding for the marginal edge of a baby carriage body formed from woven reed material, which binding comprises a channeled member having one flange shorter than the other and in which channeled member the marginal edge of the matting is received, and the matting securely clamped and held by bending the channeled member longitudinally on its widest flange, thereby imparting 40 a bend in the matting and securely clamping the binding on the matting edge.

A further object is to provide a metallic 45 binding for the marginal edge of a baby carriage matting, which binding is securely locked to the matting by folding the binding onto itself while in channeled form and simultaneously folding the matting reed ends onto themselves within the binding.

With the above and other objects in view 50 the invention resides in the combination and arrangement of parts as hereinafter set

forth, shown in the drawing, described and claimed it being understood that changes in the precise embodiment of the invention may be made made within the scope of what is claimed without departing from the spirit 60 of the invention.

In the drawing:

Figure 1 is a perspective view of a baby carriage body showing a metallic binding applied thereto. 65

Figure 2 is a perspective view of a portion of the woven matting, showing the channeled binding applied thereto and in position to be folded upon itself for securing the same to the edge of the matting. 70

Figure 3 is a view similar to Figure 2, showing the channeled member bent upon itself for securing the same to the matting edge. 75

Figure 4 is a perspective view showing the binding applied to the horizontal strand of the matting.

Figure 5 is a perspective view of one of the strands or reeds of the matting. 80

Referring to the drawing the numeral 1 designates a baby carriage body of a conventional shape, the baby carriage body comprises a bottom 2 preferably of wood, to which the lower edges of the walls 3 may be secured in any suitable manner, for instance by tacking. The walls 3 are formed from a woven material comprising horizontal strands 4 and vertical strands 5. The strands 4 and 5 are generally called reeds, however in baby carriage bodies, particularly those used for doll babies, the strands 5 are formed from a twisted specially treated paper material, which has sufficient rigidity for the purpose to which the material is put. 85 90

It is the present practice to secure to the upper edges of the walls 3 a wooden binding strip which is steamed or otherwise treated so that it can be bent to form, and to secure the upper edges of the walls to said wooden strip by nails. However it has been found 95 this is an expensive operation, the wooden binding strip easily shatters, especially after it dries out and the amount of labor increased to a point where the production of the body is relatively high. To obviate the above 100 difficulties as well as save the loss of material which is necessary for lap and extension during the securing operation, a metallic binding 6 is provided. Metallic binding 6 has sufficient rigidity so that it can be easily 105 110

bent to form when the matting is placed in position on the bottom 2, and sufficiently rigid to retain its form. Metallic binding 6 is placed on the ends of the reeds 5 in the 5 form of a channel as clearly shown in Figure 2, and at which time the narrow flange 7 engages one side of the reeds and the wide flange 8 the other sides of the reeds 5, after which the flange 8 is bent longitudinally at 10 9, which action will cause the ends of the reeds 5 to be bent upon themselves as clearly shown in Figure 3, thereby securely and positively locking the metallic binding strip on the edge of the matting, and obviating the 15 use of nails or other securing means. The reeds 5, as well as the reeds 4, if desired, may be dampened at their ends before the bending operation for facilitating the bending operation. However, the dampening operation 20 may be eliminated if desired. After the binding strip is securely clamped on a sheet of material, the sheet of material with the binding strip may be then easily and quickly bent to form in the position shown 25 in Figure 1, and the strip may be welded or otherwise secured together at 10. However, applicant does not limit himself to any particular securing means for the adjacent ends of the binding strip.

30 Referring to Figure 4 the construction and operation is the same as shown in Figures 2 and 3, with the exception the binding strip 6 is applied to the ends of the reeds 4, and in which case the operation would be 35 the same and the main difference the reversing of the positions of the reeds.

From the above it will be seen that a 40 metallic binding is provided for the bodies of baby carriages and doll baby carriages which may be easily and quickly placed on a piece of material of a woven character,

and which will obviate the use of a wooden strip which is relatively expensive and at the same time the metallic binding will have sufficient flexibility to permit flexing thereof 45 to conform to the desired curvature of the body and yet have sufficient rigidity and stability when bent to form to maintain the form produced. It will also be seen that during the bending operation the ends of 50 the reeds of the matting will be bent upon themselves to parallel positions thereby positively locking the binding strip to the reeds and in a manner whereby it will not work upwardly or downwardly, and the flange 8 55 will be downwardly disposed, consequently water or other foreign matter can not enter into the binding strip and cause rust or deterioration.

The invention having been set forth what 60 is claimed as new and useful is:—

1. In a baby carriage body a woven reed flexible material substantially U-shaped in transverse cross section, a metallic binding U-shaped in transverse cross section conforming and secured to said reed material and a bottom to which said reed material is attached, said metallic binding and bottom being the only means for maintaining the 65 reed material in flexed position. 70
2. In a baby carriage body, a flexible material substantially U-shaped in transverse cross section, a metallic binding U-shaped in transverse cross section conforming and secured to said flexible material and a bottom to which said flexible material is attached, said metallic binding and bottom being the 75 only means for maintaining the flexible material in flexed position. 78

In testimony whereof I affix my signature.

FRANK S. CHRISMAN.
